(57) **CLAIM**

The ornamental design for a bicycle carrier, as shown and described.

DESCRIPTION

FIG. 1 is a perspective view of one embodiment of the bicycle carrier showing the new design with the support arms in a raised position;

FIG. 2 is a side elevational view of the bicycle carrier shown in FIG. 1;

FIG. 3 is an opposite side elevational view of the bicycle carrier shown in FIG. 1;

FIG. 4 is a front elevational view of the bicycle carrier shown in FIG. 1;

FIG. 5 is a rear elevational view of the bicycle carrier shown in FIG. 1;

FIG. 6 is a top plan view of the bicycle carrier shown in FIG. 1;

FIG. 7 is a bottom plan view of the bicycle carrier shown in FIG. 1;

FIG. 8 is a perspective view of the bicycle carrier shown in FIG. 1 with the support arms in a lowered position;

FIG. 9 is a side elevational view of the bicycle carrier shown in FIG. 8;

FIG. 10 is an opposite side elevational view of the bicycle carrier shown in FIG. 8;

FIG. 11 is a front elevational view of the bicycle carrier shown in FIG. 8;

FIG. 12 is a rear elevational view of the bicycle carrier shown in FIG. 8;

FIG. 13 is a top plan view of the bicycle carrier shown in FIG. 8; and,

FIG. 14 is a bottom plan view of the bicycle carrier shown in FIG. 8.
